US0D1096911S

(12) **United States Design Patent** (10) **Patent No.:** **US D1,096,911 S**
(45) **Date of Patent:** **** Oct. 7, 2025**

(54) **PROJECTOR**

(71) Applicants: **Essence Technology Holdings (HK) Limited**, Hong Kong (CN); **Nexight Inc.**, Beaverton, OR (US)

(72) Inventor: **Dongwei Yang**, Hong Kong (CN)

(73) Assignees: **ESSENCE TECHNOLOGY HOLDINGS (HK) LIMITED**, Hong Kong (CN); **NEXIGHT INC.**, Beaverton, OR (US)

(**) Term: **15 Years**

(21) Appl. No.: **29/935,664**

(22) Filed: **Apr. 3, 2024**

(30) **Foreign Application Priority Data**

Mar. 28, 2024 (CN) 202430167841.6

(51) **LOC (15) Cl.** **16-02**

(57) **CLAIM**

The ornamental design for a projector as shown and described.

DESCRIPTION

FIG. 1 is a front, top, and right side perspective view of a projector according to an embodiment of my design; FIG. 2 is a rear, top, and right side perspective view thereof; FIG. 3 is a rear, bottom, and left side perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof;

FIG. 9 is a bottom plan view thereof;

FIG. 10 is an enlarged view of area 10 circumscribed in FIG. 1; and,

FIG. 11 is an enlarged view of area 11 circumscribed in FIG. 2.

1 Claim, 11 Drawing Sheets
